CONTAINER FOR CONTAINER CARS

Graham C. Woodruff, Bronxville, N. Y., assignor
to The L. C. L. Corporation, a corporation of
Delaware

Application January 3, 1936, Serial No. 57,425

2 Claims. (Cl. 294—71)

This invention relates to improvements in all-steel containers for container cars, and particularly to an all-steel container designed for shipping cement, lime and like materials in bulk. 5 More particularly, the invention relates to improvements in containers of that type in which the container is loaded through a filling opening in its top and the load discharged in bulk through a bottom outlet normally closed by drop doors. 10 One object of the invention is to provide an all-metal container having a filling inlet at its top, with novel means for reinforcing and closing said inlet, said top being formed with portions sloping from the inlet for the drainage of moisture outwardly therefrom. 15 Another object is to provide a container having an outlet at its bottom, drop doors for closing the same, controlling elements for the doors movable in housings on the outside of the container, and reinforcing corner posts on the outside of the container arranged to form guards to protect the container into and out of the container car and holding the container from shifting on the 20 car.

Still another object of the invention is to provide novel means for limiting the closing movements of the doors and sealing the spaces between the doors and between the doors and the vertical walls of the container against the escape of lading material.

With these and other objects in view, the invention consists of the features of construction, combination and arrangement of parts, herein- 35 after fully described and claimed, reference being had to the accompanying drawings, in which:—

Fig. 1 is an end elevation of a container of the type described embodying my invention.

Fig. 2 is a side elevation of the container.

Fig. 3 is a top plan view thereof.

Fig. 4 is a horizontal section through the container on line 4—4 of Fig. 2.

Fig. 5 is a view partially in end elevation, on an enlarged scale, of the lower portion of the 45 container.

Fig. 6 is a vertical section on line 6—6 of Fig. 5.

Figs. 7, 8, 9, 10, 11, 12 and 13 are vertical sections through the top portion of the container, taken, respectively, on the lines 7—7, 8—8, 9—9, 50 10—10, 11—11, 12—12 and 13—13, of Fig. 3.

Fig. 14 is a horizontal section similar to Fig. 4, but on an enlarged scale, through one of the corners of the container.

Fig. 15 is a vertical section on line 15—15 of 55 Fig. 4.

Fig. 16 is a vertical section through one end of the container showing the hinge mounting of one of the drop doors.

Fig. 17 is a vertical transverse section through the bottom of the container and the contacting edges of the drop doors and the door stop and seal. 5

Fig. 18 is a view similar to Fig. 17 showing a modified construction of the door stop and seal.

Referring now more particularly to the drawings, 1 represents the body of the container which in the example shown is of oblong rectangular form and comprises two long side walls 2, two short side walls 3 and a top wall 4, the body being provided in its top wall with a filling opening 5, and being provided at its bottom with a discharge opening 6 for the discharge of the lading from the body. 10

The walls of the body are suitably formed of steel sheets riveted and/or welded together and/or to suitable frame parts, the sheets being suitably reinforced throughout and structurally braced whenever required to resist lifting and load carrying strains. The container is adapted to rest at its base or sill portions upon the floor of a container car or compartment thereof or upon the ground or a loading platform and is provided at its top with lifting links, eyes or their equivalent 6' for engagement with the lifting elements of a crane or other lifting device in lifting and transporting the container into and out of a container car. 20

The opening 5 in the top of the container is of rectangular or oblong rectangular form, and fitted and secured in this opening is a cast-metal hatch frame 7 defining the inlet through which the cement, lime or other bulk lading is introduced. The lower portion of this hatch frame fits 25

a suitable distance down into the container to properly guide the lading thereinto while the upper portion of the hatch frame projects sufficiently above the top wall to provide for the proper formation of mounting parts thereon and to guard the filling opening against liability of flow 30

of water from the roof surface thereinto. Angle metal reinforcing beams 8 extend beneath the roof sheets along two of the sides of the opening 35

5 between the opposed long side walls 2 and are connected by angle metal supports 8' extending along the long sides of the hatch frame; and the roof sheets, reinforcing beams and supports and cast metal hatch frame are riveted or otherwise 40

rigidly united to form a roof structure which is of great strength and rigidity and moisture proof at all juncture points. The hatch opening is adapted to be closed in a moisture tight manner by a pan-shaped sheet steel hatch door 9 which 45

fits down upon and about the top of the hatch frame at all sides. The door is provided at one side with hinge members 10 connected by pintles to hinge members 11 cast integral with one of the 5 sides of the hatch frame facing one of the short sides of the container. Channeled reinforcing beams 12 extend from the hinged side of the door to and beyond the opposite side or swinging edge of the door, and are riveted or otherwise suitably 10 fastened with the hinge members 11 to the door sheet. As shown, the projecting ends of the beams 12 at the swinging side or edge of the door are notched to form keepers 13. These keepers are adapted to receive swing bolts 14 pivoted to 15 lugs 15 formed on the side of the hatch frame opposite that on which the hinge members 12 are formed, and said swing bolts carry pivoted cam members 16 whose cam surfaces are adapted to be brought into binding engagement with the 20 upper faces of the keepers 13 to fasten the hatch door securely in closed position. Suitable holding means 17 may be provided upon the door and hatch frame for the application of a seal, as shown in Fig. 13, when the container is filled for 25 shipment and the hatch door closed and fastened. In order to further ensure the conduct of rain water or other deposited moisture away from the filling inlet, the portions 18 of the roof between the hatch and short sides 3 are sloped at a suitable 30 pitch outwardly and downwardly toward said sides. When the door is swung open any moisture which may have been deposited upon its top surface will flow downward upon the adjacent surface 18 and drain by gravity off the roof of the 35 container.

The outlet or discharge opening at the bottom of the container is adapted to be closed to confine the lading by a pair of drop doors 19 arranged on opposite sides of the longitudinal center of the 40 container. Each door comprises a pressed pan-shaped sheet steel body disposed so that the marginal portions thereof form depending flanges 20. The relatively outer side edges of the doors are connected by hinges 21 to the sills of the long 45 sides of the container to adapt the doors to swing upwardly to a horizontal closed position to confine the lading and downwardly in opposite directions to vertical positions so as to leave the discharge outlet free and clear for the discharge of 50 the lading. The inner side edges of the doors are provided with Z-bar reinforcements 22 to the ends of which are secured brackets 23 each provided with an eye 23' cast integral therewith. These 55 brackets project outwardly beneath the end flanges of the doors and beyond the end sills of the container and to the eyes are attached the clevises or sockets 24 at the lower ends of door operating elements in the form of chains, cables or other flexible connections 25, cables being shown in the 60 present instance. These cables extend downwardly from the top of the container through guide housings 25' on the outside of the walls 3 and are connected at their upper ends to an eye 26 whereby the cables may be operated in unison 65 by suitable controlling means to control the doors. In order to provide spaces for the projection of the brackets 23 outwardly beyond the end sills so that the integrally cast eyes will lie underneath the 70 guide housings the bottom portions of the end sills of the container are cut away, as at 27, and these cutaway portions are reinforced by cast steel braces 28 against which the Z-bar extensions or brackets contact when the doors are in closed position. At the top of each housing is provided a cast metal cap 29 which sustains the rub-

bing wear of the cables and protects the housing therefrom. With this arrangement of the housings and cables, disposed wholly on the outside of the container, objections to the arrangement of such parts within the container loading space are 5 avoided. Also any moisture entering the housings at their upper ends is discharged at their lower ends outside the container. On the outside of the walls 3 adjacent to the corners of the container are pressed channel shaped sheet steel posts 30 10 which reinforce the container body and which project outwardly at least the same distance from the walls as the housings to provide contacting surfaces to prevent damage to the housings by contact with extraneous objects. The lower ends 15 of the posts are beveled, as at 31, to serve as guides when the container is lowered into position in a car and the outer surfaces of the posts are shaped to provide flat bearing surfaces for contact with adjacent containers, car sides or the like in order 20 to properly space the container therefrom and to prevent the container from shifting in the car.

Arranged within the container between and secured to the end walls 3 so as to be disposed above the swinging edges of the closed doors is a stop and seal member 32. This is cross-sectionally of triangular form and composed of two properly shaped metal sheets 33 extending the long way of the container at the center line and having flanged upper and lower edges riveted or otherwise united. This member is fixed in position so that its horizontal base forms a stop to limit the closing movement of the swinging edges of the doors, and in the closed position of the doors such base laps equally over such edges of the 35 doors and closes the space between the same against the leakage of the lading at this point. The sides of this triangular member 32 form sloping surfaces or deflectors over which the lading may readily flow in its discharge. Instead 40 of employing this construction of stop and seal member 32 any equivalent form of stop and seal member may be employed. An example of a modified form of center door stop and seal member which may be employed is shown in Fig. 18, 45 in which the stop and seal member is formed of two contact strips or pieces 33' of fabric belt ing secured to an inverted V-shaped or commercial angle metal shield 32', the strips 33' serving to contact the drop doors and form a tight seal 50 and the angle 32' serving as a shield or deflector like the sloping sides of the member 32, as will be readily understood.

In addition to the center door stop and seal 55 32 or 32' marginal stop and seal members 34 for the doors are also provided on the inner sides of the walls of the container body. Each of these comprises a sheet metal plate bent to form a horizontal base or stop and seal portion 35 and a sloping guide or deflector portion 36. The portions 60 35 of the members 34 are arranged to be contacted by the marginal portions of the doors and to serve as seat abutments therefor, said members also serving to seal the spaces between the container walls and door margins against the 65 escape of lading at these points. The free edges of the portions 35 and 36 are flanged for attachment by rivets or otherwise to the walls 2 and 3. To these members 34 the ends of the sheets 33 of member 32 are joined by welding. By the use of 70 the members 32 and 34 stable abutments or stops are provided against which the doors close, which abutments in the closed position of the doors seal the crevices between the doors and between the doors and container walls to prevent leakage of 75

lading, and which abutments offer no impedance in the open position of the doors to the free discharge of the lading. In addition to the protection afforded by the use of these members 32 and 34 additional protection is provided by pressing an upstanding sealing ridge or rib 37 into each door sheet. These ridges extend around the margins of each door so as to be parallel to and contact with the members 32 and 34 in the closed position of the doors, thus further sealing the joints against possibility of leakage of the lading material.

From the foregoing description, taken in connection with the drawings, the construction and mode of use of my improved construction of container for shipping cement, lime and the like material in bulk will be readily understood and its advantages appreciated by those versed in the art without a further and extended description. While the structure disclosed herein for purposes of exemplification is preferred, it is to be understood that various changes in the form and proportions of the parts and the details of construction may be made within the scope of the appended claims without departing from the spirit

or sacrificing any of the advantages of the invention.

What I claim is:—

1. A container of the character described comprising a body having a top inlet and a bottom outlet, drop doors for closing the outlet, housings on two opposite side walls of the container, controlling elements for the drop doors extending through the housings, and posts on said walls of the housings projecting outwardly from said walls to at least the same distance as the housings.

2. A container of the character described comprising a body having a top inlet and a bottom outlet, drop doors for closing the outlet, housings on two opposite side walls of the container, controlling elements for the drop doors extending through the housings, and posts on said walls of the housings projecting outwardly from said walls to at least the same distance as the housings, said posts having beveled lower ends terminating above the horizontal plane of the bottom of the container.

GRAHAM C. WOODRUFF. 25
